(57) **CLAIM**

The ornamental design for a fragrance bottle, substantially as shown and described.

DESCRIPTION

FIG. 1 is a top, left side and front perspective view of a first embodiment of our new design for a fragrance bottle; FIG. 2 is a front elevational view of the fragrance bottle shown in FIG. 1; the rear elevational view being identical thereto;

FIG. 3 is a left side elevational view of the fragrance bottle shown in FIG. 1; the right side elevational view of the fragrance bottle being identical thereto;

FIG. 4 is a top plan view of the fragrance bottle shown in FIG. 1;

FIG. 5 is a bottom plan view of the fragrance bottle shown in FIG. 1;

FIG. 6 is a top, left side and front perspective view of a second embodiment of our new design for a fragrance bottle;

FIG. 7 is a front elevational view of the fragrance bottle shown in FIG. 6; the rear elevational view identical thereto;

FIG. 8 is a left side elevational view of the fragrance bottle shown in FIG. 6; the right side elevational view of the fragrance bottle being identical thereto;

FIG. 9 is a top plan view of the fragrance bottle shown in FIG. 6; and,

FIG. 10 is a bottom plan view of the fragrance bottle shown in FIG. 6.

The broken lines and the area within the broken lines shown in FIGS. 1, 4-6 and 9-10 form no part of the claimed design.

1 Claim, 4 Drawing Sheets
